UNITED STATES PATENT OFFICE.

WALTER SCOTT, OF PLAINFIELD, NEW JERSEY.

STEREOTYPE-CASTING MOLD.

No. 799,759.

Specification of Letters Patent.

Patented Sept. 19, 1905.

Application filed July 3, 1901. Serial No. 66,975.

To all whom it may concern:

Be it known that I, WALTER SCOTT, a citizen of the United States, and a resident of Plainfield, in the county of Union and State of New Jersey, have invented certain new and useful Improvements in Stereotype-Casting Molds, of which the following is a specification.

My invention relates to improvements for casting stereotype, electrotype, or other plates either in curved or in flat form, and has for its object improvements and means whereby plates will be cast more perfectly in less time and with less labor than heretofore. Casting-boxes of this character are usually constructed so that the drag is in a horizontal position when the matrix is introduced, the cope being laid down on the drag while in this position, both cope and drag being raised to a perpendicular position when the plate is being cast, both cope and drag being lowered again to a horizontal position after the plate is cast, and the cope thereupon moved into a vertical position in order to remove the plate. The cope is usually hinged to the drag, either at its side, as in Patent No. 243,981, of July 5, 1881, or at its end, as shown in Patent No. 583,090, dated May 25, 1897, the cope being balanced by weights or springs in order to facilitate the moving of it from one position into the other. It has also been customary to bind the drag and cope together by means of clamps and screws and also to use eccentrics or cams for the purpose of separating them after the plate has been cast.

I shall describe a mold for casting stereotype or other plates embodying my invention and afterward point out the novel features in the claims.

In my improved machine I place the cope stationary on the framework and in an upright position nearly perpendicular. The drag is made movable from a horizontal position into an upright position substantially parallel to the cope, and vice versa, the means for accomplishing or effecting this being so constructed as to guide the drag so as to make it practically self-balanced or maintain it in an equilibrium when in either position or while moving from one position to another. By this means I am enabled to dispense with clamps and cams for fastening and releasing the parts. A further advantage gained by this construction lies in the fact that I am enabled to make a mold which is low at the metal-receiving end, while the drag is also of

a convenient height when in its horizontal position for receiving the matrix and removing the plate.

In order to facilitate the shaving of the plate to a uniform thickness, the cope may have circumferential rings around its surface at the point where the plate is to be cast. When a plate is to be cast with these ribs, which are usually about one-sixteenth of an inch high, it is necessary that the drag should have a sliding motion backward while it remains in a position substantially parallel with the cope, so that the ribs of the plate will be out of the grooves or rings in the cope before the drag begins to move into its horizontal position. Accordingly I construct the drag with segmental rockers adapted to rock upon fixed rails on the framework to change the drag from a horizontal to an upright position, or vice versa, and, further, with means for moving the drag in a straight line for a short distance while engaging or disengaging with the cope, the parts being preferably so arranged that the movement from the horizontal to the vertical position, and vice versa, and in a straight direction toward and away from the cope is uninterrupted.

Other improvements will appear as the specification proceeds.

In the accompanying drawings I have illustrated my invention in connection with a mold for casting curved plates; but it will of course be obvious that the invention is also applicable to molds for casting flat plates.

Figure 1 shows a side elevation of a casting-box embodying my invention with the drag in a closed position. Fig. 2 is a plan view of Fig. 1 looking in the direction of the arrow y. Fig. 3 is an end elevation of the casting-box in an open position. Fig. 4 is a portion of the circular end gage, showing the pin on which it turns. Fig. 5 shows a portion with hinge of one of the side gages. Fig. 6 shows a modification for guiding the rockers in position.

Similar letters of reference indicate corresponding parts in the different views.

A represents a framework mounting the several parts composing the casting-box. B is the cope, fastened to one end of this frame in a nearly-perpendicular position. The drag C is fixed on the segmental rockers c' and c'', having each a straight portion c¹, which roll on the friction-rolls e', and an arc-shaped portion c², which rocks on the rails e³ and e⁴. On the rockers c' and c'' are fastened the cams d'

and d^2 , which engage with the rolls e^5 and e^6 on the framework.

G is a rock-shaft extending through the frame A, to which shaft are fastened two arms 5 g' and g^2 and the operating-lever g^3 . Mounted on the rockers c' and c^2 is the rock-shaft H, to which are fastened the arms h' and h^2 . The opposite ends of these arms are connected by means of the bolts or pins i^{10} to the arms 10 g' and g^2 .

Hinged to each side of the drag C are side gages c^3 and c^4 . The hinges c^5 of these gages are raised a considerable distance above the level of the face, which is fastened to the 15 rockers c' and c^2 and the gage which comes in contact with the drag C. These hinges being so raised act to prevent the gages from lifting while they are in contact with the cope B, and thereby compel them to follow the drag 20 when it is being drawn away from the cope, and thereby prevent the plate from sticking to the cope. These gages are rabbeted on their under sides, as shown in Fig. 5 at c^6 , so as to receive the edge of the matrix when 25 placed in position to cast the plate, while a handle c^7 is attached to facilitate their manipulation. The circular end gage I is also rabbeted on the edge, as indicated at i^5 in Fig. 4, and is pivoted at each side on the pins i^6 . 30 Fastened to the upper end of the cope B is a bar b , against which the drag C rests as it is brought into an upright position to properly gage the thickness of the plates to be cast, the end gage I acting for the same purpose on 35 the lower end of the cope B. On the end of the bar b may be placed a spring-seated pin b' , which rests against the gage c^3 , so that when the drag is pulled away from the cope this pin, by means of the spring, will follow 40 against the gage, and thereby assist in pushing the plate away from the cope B. This spring-pin may be put on the bar b at both ends, although it is only shown on one end.

In order that the rockers c' and c^2 may not 45 slip and get out of position on the rails e^3 and e^4 , I employ a rack, as K, having a projection k^{10} at one end, bolted to c' , which engages with pins k' , fastened to the frame A.

The operation is as follows: When the drag 50 C is in the horizontal position, the matrix, having paper or steel tailpieces, is placed underneath the side and end gages, thus securing it in position. When in this position, the drag is about half-way between the upper and lower 55 end of the cope, which is a convenient position for inserting the matrix and for removing the plate. By means of the lever g^3 the operator rocks the drag C until it comes in an upright position parallel to, or nearly so, with 60 the cope B. At this moment the projection k^{10} engages the last of the pins k' and the cams d' and d^2 engage with the rolls e^5 and e^6 to facilitate the changing of the rocking motion to a sliding motion, and the ends of the rockers 65 c' and c^2 engage with the rolls e' , the move-

ment of the drag also being facilitated by its passing over the roll e^2 . A further motion of the lever g^3 will then, by means of the toggle-joints formed by the arms g' and g^2 and h' and h^2 , push the drag C uninterruptedly and its 70 gages up against the cope B in position to cast the plate, undue movement being prevented by the stops h^{10} and g^{10} , carried by the arms g' g^2 and h' h^2 . When the plate is cast, by 75 means of the lever g^3 the drag C is brought into the horizontal position, the side gages are folded outward by manipulating the handles c^7 , the plate is pushed forward by means of the end gage I, operated by the handles i^{15} , and is then removed in the usual way. 80

When the rack of the rockers c' and c^2 is not used, I place a stop, as L, on the frame, against which the ends of the rockers c' and c^2 at l' rest when the drag is in its horizontal position. It will thus be noted that the end of 85 the rockers c' and c^2 , coming in contact with the stop L, and the cams d' and d^2 on the rockers, coming in contact with the rolls e^5 and e^6 , will prevent the drag from getting out of its proper place. 90

In Fig. 6 I have shown a modification in which I employ an additional piece on the rockers, as R, which may be cam-shaped, adapted to engage with a pin or stop, as r' , on the framework at the time when the direction of the movement is changed. 95

The rails on which the rockers rest are A-shaped, the rockers similarly shaped, so as to guide the rockers laterally and also to prevent any metal which might fall thereon when pouring it into the mold from lodging on the rails. 100

As is usual, the cope B is made hollow and provided with a pipe or pipes inside for the circulation of water, with suitable inlet and outlet for the purpose of keeping it cool, the water also filling the hollow space in the cope. It is of course also possible to have the drag 105 stationary and the cope rocking.

In some of the claims the means for moving the movable part are described as moving it from a horizontal position to the upright position only; but it will of course be understood that the same means move it back to the original position and the claims should be so 110 construed. 115

Having thus described my invention, what I claim is—

1. In a stereotype-casting mold composed of two parts, one of which is fixed in an upright position and the other of which is movable, the combination with the movable part, of mechanism uninterruptedly carrying the movable part from a horizontal position about half-way between the upper and the lower end 120 of the fixed part into an upright position in working contact with the said fixed part. 125

2. In a stereotype-casting mold, the combination with a cope fixed in an upright position, and a drag which is movable, of mechanism un- 130

interruptedly carrying the drag from a horizontal position about half-way between the upper and the lower end of the cope into an upright position in working contact with the 5 said cope.

3. In a stereotype-casting mold composed of two parts, one of which is fixed in an upright position and the other of which is movable, the combination with the movable part, of mechanism 10 uninterrupted carrying the movable part from a horizontal position about half-way between the upper and the lower end of the fixed part into an upright position substantially parallel with the said fixed part and then in a straight direction against the latter.

4. In a stereotype-casting mold, the combination with a cope fixed in an upright position, and a drag which is movable, of mechanism uninterrupted carrying the drag from a horizontal 20 position about half-way between the upper and the lower end of the cope into an upright position substantially parallel with the said cope, and then in a straight direction against the latter.

25 5. In a stereotype-casting mold composed of two parts, one of which is fixed in an upright position and the other of which is movable, means for moving the movable part from a horizontal position about half-way between the upper and the lower end of the fixed part into an upright position substantially parallel with the said fixed part, means for moving the movable part in a straight direction against the fixed part, both movements being effected as 30 an uninterrupted operation.

40 6. In a stereotype-casting mold, the combination with a cope fixed in an upright position, and a drag which is movable, of means for moving the drag from a horizontal position about half-way between the upper and the lower end of the cope into an upright position substantially parallel with the said cope, means for moving the drag in a straight direction against the cope, both movements being 45 effected as an uninterrupted operation.

50 7. In a stereotype-casting mold composed of two parts, one of which is fixed in an upright position and the other of which is movable, the combination with the movable part, of a rocker, and means for operating the same, uninterrupted carrying the movable part from a horizontal position about half-way between the upper and lower end of the fixed part into an upright position in working contact with the 55 said fixed part.

60 8. In a stereotype-casting mold, the combination with a cope fixed in an upright position, and a drag which is movable, of a rocker, and means for operating the same, uninterrupted carrying the drag from a horizontal position about half-way between the upper and the lower end of the cope into an upright position in working contact with the said cope.

65 9. In a stereotype-casting mold composed of two parts, one of which is fixed in an upright

position and the other of which is movable, the combination with the movable part, of a rocker, and means for operating the same, uninterrupted carrying the movable part from a horizontal position about half-way between the upper and the lower end of the fixed part into an upright position substantially parallel with the said fixed part and then in a straight direction against the latter.

10 70 10. In a stereotype-casting mold, the combination with a cope fixed in an upright position, and a drag which is movable, of a rocker, and means for operating the same, uninterrupted carrying the drag from a horizontal position about half-way between the upper and the lower end of the cope into an upright position substantially parallel with the said cope and then in a straight direction against the latter.

20 80 11. In a stereotype-casting mold composed of two parts, one of which is fixed in an upright position and the other of which is movable, a rocker, and means for operating the same, adapted to move the movable part from a horizontal position about half-way between the upper and the lower end of the fixed part into an upright position substantially parallel with the said fixed part, means for moving the movable part in a straight direction against the fixed part, both movements being effected as 90 an uninterrupted operation.

30 95 12. In a stereotype-casting mold, the combination with a cope fixed in an upright position and a drag which is movable, of a rocker, and means for operating the same, adapted to move the drag from a horizontal position about half-way between the upper and the lower end of the cope into an upright position substantially parallel with the said cope, means for moving the drag in a straight direction against the cope, both movements being effected as 100 an uninterrupted operation.

40 105 13. In a stereotype-casting mold composed of two parts, one of which is fixed in an upright position and the other of which is movable, the combination with the movable part, of mechanism carrying the movable part from a horizontal position about half-way between the upper and the lower end of the fixed part into an upright position and simultaneously 110 therewith toward the fixed part, and then into working contact with the said fixed part.

50 115 14. In a stereotype-casting mold, the combination with a cope fixed in an upright position and a drag which is movable, of mechanism carrying the drag from a horizontal position about half-way between the upper and the lower end of the cope into an upright position, and simultaneously therewith toward the cope, and then into working contact with the said cope.

60 120 15. In a stereotype-casting mold composed of two parts, one of which is fixed in an upright position and the other of which is movable, the combination with the movable part, 130

- of mechanism carrying the movable part from a horizontal position about half-way between the upper and the lower end of the fixed part into an upright position substantially parallel 5 with the said fixed part, and simultaneously therewith toward the fixed part, and then in a straight direction against the said fixed part.
16. In a stereotype-casting mold, the combination with a cope fixed in an upright position and a drag which is movable, of mechanism carrying the drag from a horizontal position about half-way between the upper and lower end of the cope into a position substantially parallel with the said cope and simultaneously therewith toward the cope, and then in a straight direction against the latter.
17. In a stereotype-casting mold composed of two parts, one of which is fixed in an upright position and the other of which is movable, means for moving the movable part from a horizontal position about half-way between the upper and the lower end of the fixed part into an upright position substantially parallel with the said fixed part, and simultaneously therewith toward the fixed part, and means for moving the movable part in a straight direction against the said fixed part.
18. In a stereotype-casting mold, the combination with a cope fixed in an upright position, and a drag which is movable, of means for moving the drag from a horizontal position about half-way between the upper and the lower end of the cope into an upright position substantially parallel with the said cope, and simultaneously therewith toward the cope, and means for moving the drag in a straight direction against the cope.
19. In a stereotype-casting mold composed of two parts, one of which is fixed in an upright position, and the other of which is movable from a horizontal position about half-way between the upper and lower end of the fixed part and into working contact with the 45 said fixed part, the combination with the movable part, of toggles for effecting such movement.
20. In a stereotype-casting mold, the combination with a cope fixed in an upright position, and a drag which is movable from a horizontal position about half-way between the upper and lower end of the cope and into working contact with the same, of toggles for effecting such movement of the drag.
21. In a stereotype-casting mold consisting of two parts, one of which is fixed in an upright position and the other of which is movable, a segmental rocker adapted to be operated to move the said movable part from an upright position to a horizontal position and back, and toggles for operating the rocker to move the movable part into either position.
22. A stereotype-casting mold consisting of a cope fixed in an upright position and a drag 65 which is movable, a segmental rocker adapted

to be operated to move the said drag from an upright to a horizontal position and back, and toggles for operating the rocker to move the drag into either position.

23. In a stereotype-casting mold composed 70 of two parts, one of which is fixed in an upright position, and the other of which is movable from a horizontal position about half-way between the upper and lower end of the cope and into working contact with the said cope, the combination with the movable part, of mechanism for guiding and effecting the movement thereof constructed so as to maintain the movable part in an equilibrium.

24. In a stereotype-casting mold, the combination with a cope fixed in an upright position, and a drag which is movable from a horizontal position about half-way between the upper and lower end of the cope and into working contact with the said cope, of mechanism for guiding and effecting the movement of the drag, constructed so as to maintain the said drag in an equilibrium.

25. A stereotype-casting mold consisting of 80 two parts, one part fixed in an upright position on a framework, and the other part movable on said framework, a segmental rocker for rocking the movable part from an upright to a horizontal position and back, and a stop at each end of the path of the segmental 85 rocker whereby the distance of its travel is limited.

26. A stereotype-casting mold consisting of 90 two parts, one part fixed in an upright position on a framework, and the other part movable on a frame having rails, segmental rockers for rocking the movable part from an upright to a horizontal position and back, a stop at each end of its path, and contacting means 100 between the said stops whereby the distance 105 of the travel of the segmental rocker is limited and slipping on the rails prevented.

27. In a stereotype-plate-casting mold consisting of a cope and a drag, hinged side gages fastened to the drag and adapted to receive a 110 matrix, a spring-seated stop fixed to the cope, and means for bringing the drag into position for casting, the spring-seated stop resting against the gage and keeping it in place until it is in contact with the cope, and also while it 115 is leaving the cope.

28. In a stereotype-casting mold comprising a cope and a drag, the combination with the drag, of side gages as c^3 and c^4 having the hinges c^5 raised a considerable distance above 120 the face of the drag, for the purposes as set forth.

29. In a stereotype-casting mold, a side gage as c^3 or c^4 provided with one or more hinges c^5 raised a considerable distance above the face 125 of the said gage, for the purposes as set forth.

30. In a stereotype-casting mold composed of two parts, one of which is fixed in an upright position, and the other of which is movable from a horizontal position about half-way 130

between the upper and lower end of the fixed part and uninterruptedly into working contact with the said fixed part, the combination with the movable part, of toggles for effecting such movement.

31. In a stereotype-casting mold, the combination with a cope fixed in an upright position, and a drag which is movable from a horizontal position about half-way between the upper and lower end of the cope and uninterruptedly into working contact with the same, of toggles for effecting such movement of the drag.

32. In a stereotype-casting mold composed of two parts, one of which is fixed in an upright position, and the other of which is movable from a horizontal position about half-way between the upper and lower end of the cope and uninterruptedly into working contact with the said cope, the combination with the

movable part, of mechanism for guiding and effecting the movement thereof constructed so as to maintain the movable part in an equilibrium.

33. In a stereotype-casting mold, the combination with a cope fixed in an upright position, and a drag which is movable from a horizontal position about half-way between the upper and lower end of the cope and uninterruptedly into working contact with the said cope, of mechanism for guiding and effecting the movement of the drag, constructed so as to maintain the said drag in an equilibrium.

Signed at New York, in the county of New York and State of New York, this 28th day of May, A. D. 1901.

WALTER SCOTT.
